(57) **CLAIM**

(22) Filed: **May 15, 2001**

The ornamental design for a self-centering mobile adapted to display photographs vertically and/or horizontally off an arc armature, as shown and described.

Related U.S. Application Data

DESCRIPTION

(62) Division of application No. 29/117,086, filed on Jan. 14, 2000.

The view is a perspective view of a self centering mobile adapted to display photographs vertically and/or horizontally off an arc armature, showing my new design.

(51) LOC (7) Cl. **06-07**

Claimed is a design for a self-centering mobile adapted to display photographs vertically and/or horizontally off an arc armature comprising three interchangeable portions: one or more mobile portions, an arc armature portion and a supporting structure portion.
